UNITED STATES PATENT OFFICE.

ERNEST A. KERSTEIN, OF UNION, NEW JERSEY, ASSIGNOR TO AMERICAN METER COMPANY, OF NEW YORK, N. Y., A CORPORATION OF DELAWARE.

CHECK-VALVE.

1,285,220.

Specification of Letters Patent. Patented Nov. 19, 1918.

Application filed February 14, 1918. Serial No. 217,218.

To all whom it may concern:

Be it known that I, ERNEST A. KERSTEIN, a citizen of the United States, residing at Union, in the county of Hudson and State 5 of New Jersey, have invented new and useful Improvements in Check-Valves, of which the following is a specification.

The present invention relates to check valves for use in connection with systems 10 for delivering illuminating gas and other fluids of like character; and it proposes, briefly, an improved device of the general class indicated, which is designed to prevent back pressure in the piping comprised 15 in such systems and which is applicable primarily, though not restrictedly, as an adjunct to, or attachment for, a standard gas meter, to avoid injury to the meter parts due to their backward movement under the 20 pressure of the gas.

According to the invention, there is provided within the receiving chamber, which contains the usual valve gear, a smaller casting or chamber wherein is housed a supplemental valve. This supplemental valve normally rests on its seat, and the gas, after having been measured, causes said valve to lift, enters said housing through the valve opening and then passes therefrom to the 30 outlet pipe, instead of flowing directly to the latter in the ordinary way. Conversely, if the pressure in the outlet pipe exceeds that in the inlet, the supplemental valve will be forced against its seat and communication 35 between the valve housing and the receiving chamber will be interrupted, with the result that reverse movement of the measuring and indicating mechanism is completely prevented.

40 An embodiment of the invention is illustrated in the accompanying drawing, wherein:

Figure 1 is a vertical sectional view, showing the invention applied to a gas meter, 45 with the check valve in its normal position.

Fig. 2 is a fragmental plan view.

Fig. 3 is a detail section, showing the valve closed.

Referring more particularly to said drawing, 50 5 and 6 indicate, respectively, the upper and lower or main chambers into which

the interior of the meter is divided by the horizontal partition plate or table 7, and 8 and 9 the inlet and outlet pipes; the meter here represented being of standard construction, though any other suitable or preferred form of meter may be employed. The upper chamber 5 ordinarily constitutes the receiving chamber and contains the usual valve gear and indicating mechanism, the 55 latter being omitted from the present showing as forming no part of the invention, while the lower chamber 6 contains the usual bellows mechanism, illustration of which is likewise omitted for the same reason. In the present construction, however, the gas chamber is constituted by a substantially-pentagonal inclosure or case 10, which is provided within the chamber 5 and is supplied with gas by a horizontal conduit 60 11, disposed longitudinally and centrally of the table 7 and having its top wall formed by said table. The conduit extends from end to end of the table and is provided with an outlet opening 12 between its ends, this 65 opening being located in the top wall of the conduit and so disposed as to discharge the gas into the gas chamber or case 10; the gas flowing through the conduit being 70 deflected through said opening by an inclined partition plate 13. The usual opening at the far end of the conduit communicating with the outlet pipe 9 is blocked by a closure plate 14, and the gas, instead of flowing into said pipe through that open- 75 80 85 90 95 100

The supplemental valve device, which, as previously stated, constitutes the subject matter of the invention, is arranged within a smaller case or housing 17, mounted in the gas chamber 10 upon the table 7 and located above the points where the converging outlet channels 16 open into the conduit 11; communication between the latter and the said housing being established by way of an opening 18 formed in the top wall of the conduit and having its edge turned continuously upward so as to provide an annular valve seat 19. The passage of the gas through the opening 18 is controlled by means of the check valve 20, which, in the construction illustrated, takes the form of a disk or plate, pivoted to one end of a lever 21. The said lever is fulcrumed centrally in an upstanding bracket 22, suitably mounted in the housing, and its other arm carries a counterbalance weight 23, the arrangement being such that the valve rests upon its seat when the pressure on both sides thereof is the same, which is the case when no flow takes place, but will be raised from said seat upon a very slight increase in pressure on the inlet side in order to permit the gas, after having passed from the channels 16 into the conduit, to enter the housing and escape therefrom into the outlet pipe 9 by way of an opening 24 provided in that portion of the adjacent side wall of the meter which is common to the housing 17 and said outlet pipe 9.

The normal movement of the gas will be apparent from the foregoing, and hence, requires no extended explanation, it being considered sufficient to state that, on entering the conduit 11 from the inlet pipe 8, the gas flows through said conduit until it reaches the opening 12, whereupon it passes into the gas chamber 10; then through the ports controlled by the valve gear to the bellows mechanism where it is measured in the usual way and then passes through the proper ports to the channels 16; thence back into the conduit 11 where it passes through the opening 18, raising the valve 20 and flowing into the valve housing 17, from which it finally escapes into the outlet pipe 9 through the opening 24, all as indicated by the arrows in Fig. 1. If, however, the pressure on the outlet side should increase, from any cause, to a point where it becomes equal to or exceeds that on the inlet side of the meter, then the gas will be forced backward through said pipe, and through the opening 24 into the valve housing; but instead of being permitted to escape therefrom and reenter the measuring chamber, the pressure of the gas in said housing acts directly upon the check valve 20 and forces it tightly against its seat 19,

thereby shutting off communication between the housing and the conduit until the pressure in the outlet pipe again falls below that on the inlet side, whereupon the valve automatically opens under the influence of the pressure on the inlet side.

While the invention has been shown and described as applied to a standard or other gas meter, it will be understood, as previously stated, that no limitation to such use, nor, in fact, even to a fluid meter, is contemplated, excepting in so far as implied by the terms of the appended claims, since the invention is capable of being installed and utilized in a line of pipe or in the outlet pipe of the meter to prevent back pressure.

I claim as my invention:

1. A fluid delivery system of the character specified comprising a conduit through which the fluid passes, said conduit having an outlet and a partition thereacross in advance of the said outlet, the said outlet opening into means having communication with the conduit in advance of the partition, and an outlet inclosure also communicating with said conduit in advance of the partition and having a valve therein operating to close communication between said inclosure and the conduit when the pressure in the inclosure is the same as or exceeds that in the conduit.

2. In a fluid delivery system, the combination of a conduit through which the fluid is to pass, said conduit having an intermediate partition thereacross forming an obstruction to the passage of the fluid, a housing having separate inlet and outlet ports communicating with the conduit at opposite sides of said partition whereby the fluid is caused to pass through said housing on reaching the partition, and a valve in said housing adjacent to the outlet member of the conduit and operable automatically to close the inlet port by the rise of pressure in the conduit on the outlet side of the partition.

3. In a fluid meter, a receiving chamber, a fluid supply conduit in port communication with the chamber, the fluid supply conduit having inlet and outlet pipe members a partition within and extending across the supply conduit for deflecting the fluid from the conduit through the port in communication with the receiving chamber, a housing disposed within said chamber and having an outlet port opening into the outlet pipe member, the housing being isolated from communication with the said chamber and having an inlet port communicating with the supply conduit in advance of the partition, means for conducting fluid from said receiving chamber to the supply con-

duit in advance of the partition to effect a flow of the fluid into the housing, and a valve in said housing automatically operable to close the inlet port of the housing 5 when the pressure of the fluid in the outlet pipe member is the same as or exceeds that in the supply conduit.

In testimony whereof I have hereunto set my hand in presence of two subscribing witnesses.

ERNEST A. KERSTEIN.
